US0D1079012S

(12) **United States Design Patent** (10) **Patent No.:** **US D1,079,012 S**
(45) **Date of Patent:** **** Jun. 10, 2025**

(54) **HEARING AID**

(71) Applicant: **GN Hearing A/S**, Ballerup (DK)

(72) Inventor: **Henrik Hetz Christiansen**,
Copenhagen K (DK)

(73) Assignee: **GN HEARING A/S**, Ballerup (DK)

(**) Term: **15 Years**

(21) Appl. No.: **29/935,002**

(22) Filed: **Mar. 28, 2024**

Related U.S. Application Data

(62) Division of application No. 29/840,959, filed on Jun. 2, 2022.
